UNITED STATES PATENT OFFICE.

OSKAR CARLSON, OF FELCH, MICHIGAN.

GRAIN-DOOR.

1,005,510.

Specification of Letters Patent. Patented Oct. 10, 1911.

Application filed March 1, 1911. Serial No. 611,677.

To all whom it may concern:

Be it known that I, OSKAR CARLSON, a citizen of the United States, residing at Felch, Dickinson county, Michigan, have invented certain new and useful Improvements in Grain-Doors, of which the following is a specification.

This invention relates to grain door construction, especially doors for railway grain 10 cars.

The object of the invention is to provide grain doors of simple construction, of convenient manipulation and control, and easy installation.

With this object in view the invention consists of the novel construction, combination and arrangement of parts hereinafter described in detail, illustrated in the accompanying drawing and incorporated in the 20 appended claims.

In the drawing—Figure 1 is a side elevation showing the outer side of a portion of a car with my invention applied thereto. Fig. 2 is a similar view showing the grain 25 doors partly opened and with the latch-lever in position for the operator's control of the extent of initial opening of the doors. Fig. 3 is a cross section of a portion of a car and edge views of the grain door in both 30 open and closed positions. Fig. 4 is a perspective detail view.

In the several views 2 represents one of the sides of a railway car, 3 the usual side door opening and 4 the usual slide-door 35 running on rails 5 and 6.

7 and 8 represent two sections of a grain door hinged together at their junction line 9 to swing outwardly, 10, 10 in Fig. 3 representing the hinges. The two door sections 40 7 and 8 are supported vertically upon a rod 11 engaged by ears or eyes 12 and 13 upon straps 14 secured to said door sections, and the doors are slidable upon said rod within the limits of stops 15 and 16 for the door 7 45 and similar stops 17 and 18 for the door 8. These stops are preferably collars shrunk upon the rod 11. The latter rod is itself movable vertically on vertical rods 19 and 20 within the car, the rod 11 being provided 50 with ears or eyes 21 and 22 which engage the respective rods 19 and 20. The latter have each a bent or horizontal portion 23 at the rod's upper end and a similar bent or horizontal portion 24 at its lower end, so 55 that when the doors 7 and 8 are in their closed position shown in Figs. 1 and 3 the

eyes on the ends of the horizontal rod 11 are engaged with the horizontal portions 24 of the vertical rods which prevents prying up or lifting the doors from the outside before they are unlocked to swing open on their hinges. The horizontal upper portions 23 of the vertical rods 19 and 20 support the eyes 21 and 22 when the grain doors are fully opened and swung into horizontal position against the ceiling of the car, this complete suspension of the grain doors being completed by means of a hook 25 suspended from the ceiling 26 of the car, said hook being, as shown in Fig. 3, engaged with 60 the lower edge of the grain door, or grain door sections 7 and 8.

The two sections 7 and 8 of the grain door are locked against movement on their hinges 10 by means of a latch-bar 27 pivoted at 28 65 within a strap 29 to the door section 7. The door section 8 is provided with a catch 30 which is adapted to engage the latch-bar 27. The free end of the latch-bar has pivoted thereto at 31 a lever or handle 32, which 70 when the grain door sections are closed as in Fig. 1, is folded over the latch-bar 27 and when the doors are to be opened is swung out away from the latch-bar as an extension or handle therefor projecting, as 75 shown in Fig. 2, to a point laterally of the car door opening 3. This handle extension is for the purpose of enabling the person about to open the grain doors to stand at the side of the door opening and control the 80 grain door sections opening movement on their hinges and limit the initial flow of grain to the desired extent. In Fig. 2 the door sections are shown partly open, or to form a small angular opening at 34 between 85 the door sections and the floor of the car, the size of the opening at 34 being, as stated, regulated by the operator's control of the handle 32. A stop or support 35 is provided for the latch-bar to drop into. On one 90 of the door sections 7 and 8 is mounted a strap having an S-shaped portion providing two hooks 36 and 37, the hook 36 being engaged with the rod 11 to help support the doors when alined or closed at their hinge 95 junction 9. The hook 37 is engaged with a short rod 38 secured to the inner side of the car near its top to support the upper edges of the door sections in their horizontal out-of-the-way position against the ceiling of the 100 car as shown in Fig. 3, the hook 37 serving principally to support the doors against 105 110

swinging on their hinges from said position. The main supports for the upper edges of the door sections 7 and 8 are, as previously stated, the horizontal upper portions 23 of the vertical rods 19 and 20. The latch-bar 27 passes under the catch 30 and when the handle 32 is folded over the latch-bar it is also folded over the catch 30, and a recess 39 is provided for the latter in the handle 32. In the recessed portion is a slot 40 to be engaged by a U-bolt or staple 41 on the catch 30. The handle is locked on the staple by means of a pin 42 which is engaged with the staple outside of the handle, as shown in Figs. 1 and 3. The pin 42 is attached to a short chain 43 which is suspended from an eye bolt 44, which prevents loss of the pin. In the lower end of said pin is an eye 45 through which may be threaded the usual seal strap, so that the grain doors, as well as the side-door of the car, may be sealed. When thus sealed the grain doors cannot be opened without breaking the seal, or a lock taking the place of the seal, as the doors cannot be pried upward by reason of the horizontal portions 24 of the vertical rods engaging the eyes on the ends of the horizontal rod 11.

In operation the handle 32 will be released by removing the staple pin, swung out as in Fig. 2 and held by the operator until the desired amount of grain is permitted to escape. A small quantity may be taken and the doors closed again, or they will be gradually opened until relieved entirely from grain pressure from behind. When enough grain has been released to permit convenient entrance to the car the two door sections are slid up on the vertical rods, the eyes of the rod 11 engaged with the horizontal portions 23 of the vertical rods, the hook 37 engaged with the short rod 38 and the door swung into horizontal position, as shown in Fig. 3, and thus supported with the aid of the hook 25 until the car is unloaded.

If it is desired to temporarily remove the grain door sections entirely they may be con-

veniently uncoupled from the horizontal rod 11, the latter supported until needed again upon the upper horizontals 23 of the vertical rods and the grain door sections stored in any convenient place, the vertical rods 19 and 20, the horizontal rod 11 and the hook 25 remaining as the only fixed parts of the car.

Having thus described my invention, I claim as new and desire to secure by Letters Patent—

1. The combination with a door opening, of door-sections spanning said opening, said sections hinged together for opening movement on their hinges, a rod upon which said door sections are slidably mounted for vertical support during angular movement relative to each other, vertical rods upon which said rod is slidably mounted, and means for locking the latter rod against vertical movement.

2. The combination with a door opening, of a pair of door sections spanning said opening, said sections pivoted together at their junction, means for locking said door sections against movement on their pivots, means supporting said doors laterally for vertical movement, means for locking the door sections against vertical movement, and means for supporting said sections out of the way overhead in a horizontal position.

3. A grain door consisting of two sections hinged together for angular opening and closing movement, means supporting said door sections for sliding movement in connection with their angular movement, means supporting the sections for movement vertically as a single door, and means operable from one side of the door-opening for controlling the combined angular and sliding movement of said door sections.

In testimony whereof I have hereunto set my hand in the presence of two subscribing witnesses.

OSKAR CARLSON.
